UNITED STATES PATENT OFFICE.

ALFRED GASKILL, OF PHILADELPHIA, PENNSYLVANIA, ASSIGNOR TO
EUGENE VALLENS AND FREDERICK ROTHSCHILD, OF CHICAGO,
ILLINOIS.

DESIGN FOR A JAR.

SPECIFICATION forming part of Design No. 25,617, dated June 9, 1896.

Application filed April 1, 1896. Serial No. 585,824. Term of patent 14 years.

To all whom it may concern:

Be it known that I, ALFRED GASKILL, a citizen of the United States, residing in Philadelphia, Pennsylvania, have invented a certain Design for a Jar, of which the following is a specification.

My design for a jar is fully shown in the accompanying drawings, in which—

Figure 1 represents a side view of the jar; Fig. 2, a sectional view of the same; and Fig. 3, a sectional plan view on the line 3 3, Fig. 2.

The jar comprises two parts—namely, the body A and the top or cap B, the jar being of cylindrical form and having surface ornamentation of a character clearly shown in the drawings. The body has at the base a projecting ring or rib *a* with beveled upper and lower

edges and a plain cylindrical upper portion *b* with beveled lower edge. Between the base-ring *a* and the upper ring *b* of the body are a series of parallel and contiguous bands *d*, each composed of a series of adjoining projecting ornaments in the form of truncated pyramids *g* and half-pyramids *i*.

I claim—

The design for a jar-body A, substantially as described and shown in the drawings.

In testimony whereof I have signed my name to this specification in the presence of two subscribing witnesses.

ALFRED GASKILL.

Witnesses:

WILL. A. BARR,

FRANK E. BECHTOLD.
